UNITED STATES PATENT OFFICE:

WALTER H. VAUGHAN, OF DETROIT, MICHIGAN.

HEEL.

1,122,445.

Specification of Letters Patent. Patented Dec. 29, 1914.

Application filed March 19, 1914. Serial No. 825,935.

To all whom it may concern:

Be it known that I, WALTER H. VAUGHAN, a citizen of the United States of America, residing at Detroit, in the county of Wayne and State of Michigan, have invented certain new and useful Improvements in Heels, of which the following is a specification, reference being had therein to the accompanying drawings.

This invention relates to heels and more particularly to that type of cushion heel having renewable tread pieces adapted to be renewed when worn or injured, or repositioned whereby the tread pieces are evenly worn. It is in this connection that the present invention is an improvement upon the heel disclosed by my Patent #1,088,115, granted February 24th, 1914.

The present invention aims to provide a heel having renewable and detachable resilient tread pieces that can be easily and quickly repositioned and evenly worn, and novel means is employed for preventing the tread pieces from cracking or breaking loose from the fastening means employed for retaining the tread pieces in position.

The invention further aims to provide a cushion heel having yieldable tread pieces that prevent slipping upon smooth surfaces, the tread pieces being cupped or shaped to produce a suction action when the heel contacts with a surface and thereby preclude any possibility of a wearer of the heel slipping.

The invention will be better understood when reference is had to the drawing and the detail description thereof.

In the drawing, Figure 1 is a bottom plan of the heel with a tread piece thereof detached; Fig. 2 is a side elevation of the same partly broken away and partly in section, and Fig. 3 is a perspective view of a detached tread piece.

The reference numeral 1 denotes a portion of a shoe having a heel 2 of less depth than an ordinary heel and secured to the heel 2 by a plurality of screws 3 or similar fastening means is a heel body 4 of suitable contour and proportions, said heel body being made of rubber or like resilient or cushioning material. The heel body 4, adjacent to the outer edges thereof, is provided with a plurality of tapering sockets 5, said sockets tapering from the outer ends thereof to a point in proximity to the inner side of the heel body, which is provided with openings

6 in communication with said sockets. The openings 6 are of less diameter than the inner or small ends of the sockets, thereby providing annular shoulders 7. The openings 6 are triangular in cross section and are adapted to receive the triangular shanks 8 of tapering tread pieces 9. The shanks 8 completely fill the openings 6 and the inner or small ends of the tread pieces bear upon the shoulders 7 with the walls of the tread pieces snugly fitting against the walls of the sockets. The outer large ends of the tread pieces protrude from the large ends of the sockets 5 into a common plane parallel with the heel body 4.

The tread pieces 9 have the outer ends thereof provided with concentric recesses 10 in communication with screw openings 11 of less diameter than the recesses. Embedded within the tread pieces, at the junction of the recesses 10 and the openings 11, are wear plates 12 having openings aligning with the screw openings 11. The wear plates 12 are of a greater diameter than the recesses 10 and the openings of said plates are adapted to receive screws 13 that extend through the openings 11 into the heel 2 of the shoe for retaining the tread pieces in the sockets 5 of the heel body. The heads of the screws 13 engage the wear plates 12 and consequently the tread pieces 9 are not cut or injured by the screws when attaching or detaching the tread pieces.

Besides the recesses 10 providing clearance for the heads of the screws, whereby said heads are counter-sunk, said recesses add resiliency to the tread pieces by allowing the walls thereof to yield and each tread piece squarely engages the surface to which it is brought into contact. By tapering the tread pieces the walls of the sockets firmly brace said tread pieces and tend to retard too great a compression of the same.

It is through the medium of the triangular shanks 8 that the tread pieces can be repeatedly repositioned whereby the edges of the tread pieces can be uniformly worn and the longevity of the same increased. As the tread pieces at the rear end of the heel generally receive greater wear than the tread pieces at the forward end of the heel, it will be an extremely easy matter to shift the tread pieces around whereby all of said tread pieces are evenly worn.

One embodiment of my invention has been illustrated, but it is to be understood that

the structural elements are susceptible to such variations and modifications as fall within the scope of the appended claims.

What I claim is:

- 5 1. A cushion heel comprising a heel body provided with tapering sockets and triangular shaped openings in communication with said sockets, tapering tread pieces mounted in said sockets and provided with shanks extending into said openings, wear plates embedded in said tread pieces, and means extending through said wear plates adapted to retain said tread pieces in engagement with said heel body.
  - 10 15 2. A cushion heel comprising a heel body provided with sockets and openings in communication with said sockets, tread pieces detachably mounted in the sockets of said heel body and provided with shanks extending into said openings and said shanks being shaped and arranged to prevent rotation of said tread pieces in said sockets, wear plates embedded in said tread pieces, and means extending through said wear plates for retaining said tread pieces in the sockets of said heel body.
  - 20 25 3. A cushion heel comprising a heel body provided with tapering sockets and openings in communication with said sockets, taper-
- ing tread pieces arranged in said sockets and 30 having shanks non-rotatably held in the openings of said heel body, wear plates counter-sunk in said tread pieces, and means extending through said wear plates adapted to retain said tread pieces in engagement 35 with said heel body.
4. The combination with a shoe heel, of a heel body arranged upon said shoe heel and provided with tapering sockets and 40 openings in communication with said sockets, tapering tread pieces arranged in said sockets and having shanks non-rotatably held in said openings, said tread pieces having recesses formed therein, wear plates mounted in said tread pieces at the inner 45 ends of the recesses thereof, and means extending through said wear plates and the shanks of said tread pieces into said shoe heel for simultaneously retaining said heel body and said tread pieces in engagement 50 with said shoe heel.

In testimony whereof I affix my signature in presence of two witnesses:

WALTER H. VAUGHAN.
